[57] ABSTRACT

An apparatus for removing sample pieces from continuously moving materials in open width of textiles, paper, plastics and the like, comprising a mounting support, a preferably circular punching knife, a plane punching plate and an actuating appliance for the knife.

The mounting support allows the materials to pass between the knife and the punching plate. Samples are cut, when the edge of the knife is touching the punching plate. This is done in a very short time, because the knife is actuated by detonation of a cartridge. The samples are collected in a tray beyond the punching plate. The samples are pushed through an aperture in the punching plate, which is somewhat smaller than the samples, into the tray by a blast of air, caused by the movement of the knife.

**APPARATUS FOR THE SAMPLING FROM
CONTINUOUSLY MOVING MATERIALS**

The invention relates to an apparatus which allows the sampling of textile, paper and synthetic materials during continuous processing operations in open width and at a predetermined moment.

Textiles, paper, films, synthetic materials are generally processed nowadays in continuous, open width operations. For the purpose of controlling quality of the goods and performance of machines it is advisable to check color, weight, moisture contents and other factors in regular intervals by taking samples.

Sampling up to now requires stopping the machine. This reduces the output, risks tearing a fabric and very often also adversely effects the character of a sample. The new apparatus avoids all these problems.

The present invention is comprising a punch knife in the shape of the sample to be taken, fastened to a bolt, which is suddenly pushed down vertically onto the material and impacts on a plane punching plate arranged on the reverse side of the material. By the knife edge touching this plate, the sample is punched out in an extremely short time. The knife retracts at such a speed that it punches the sample without impeding the movement of the fabric and without jamming the apparatus through impact with the moving material.

Characteristic elements of the invention are illustrated in the accompanying drawings of one of several alternatives to knife propulsion and apparatus support:

FIG. 1 shows the sample-puncher operated by a cartridge, 30 and

FIG. 2 shows a complete apparatus fixed to a fork-type support.

In FIG. 1 a sectional view of a web 10 is shown. Above the said web there is the circular knife 11 in the bell-shaped mounting support 12 which is fastened to the bolt 13. The said bolt is arranged in the cylindric housing 14 in the bushes 15 and 16. The said bolt is kept in the shown limit position by the spring 17. The cartridge 18 is inserted in bush 16. Head 19 is screwed on to the bush 16. Head 19 contains the striker 20 and the trigger 21. The apparatus is prepared for punching by withdrawing striker 20. The elements described before are connected with a mounting support by means of flange 22.

The ring 23 is fixed in a concentric position to the knife in a cylindric support 24 with an interposed rubber ring 25. The support 24 also serves as collecting tray for the punched-out sample. Lateral openings 26 permit to remove the sample. Ring 23 is somewhat smaller in the inner diameter than the edge of the knife. The knife is made from hardened steel and the ring from softer material, for example, from brass. The bell-shaped mounting support 12 produces a blast during the movement, whereby the punched-out sample is shifted to the support 24. The support 24 is fastened by screws 27.

Cup springs 28, rubber ring 25 and coil spring 17 supply the energy for speeding up the retraction movement of the knife; they also allow adjustment of elements 11 and 23 which touch each other.

5 In FIG. 2 the fork-type mounting support 30 encloses a selvedge of web 10. At one fork end of the said mounting support the actuating appliance 29 is provided for the punch knife 11, whereas the other fork end holds the sample collecting tray 24 with the ring 23.

10 When taking a sample the fork-type support 30 may either be put down on to a suitable part of the machine or held at handle 32 and the actuating appliance 29. Handle 31 serves for transporting the apparatus.

It should be further understood, that the present disclosure 15 is for the purpose of illustration only and that the invention includes all modifications and equivalents which fall within the scope of the appended claims.

We claim:

20 1. An apparatus for removing sample pieces from continuously moving materials in open width of textiles, paper, plastics and the like comprising:

a. a mounting support, allowing said materials to pass between upper and lower parts of said apparatus;

b. an actuating appliance connected to the upper part of said mounting support, said actuating appliance consisting of a cylindrical housing, a bolt sliding in bushes inserted in both ends of said housing, a spring to hold said bolt in upper position, said upper bush containing a cylindrical hole to insert a cartridge, a head fixed on top of said upper bush containing a striker, and a trigger to ignite said cartridge;

c. a preferably circular knife connected with said bolt;

d. a plane punching plate inserted in an support connected to the lower part of said mounting support.

35 2. The invention according to claim 1 wherein said punching plate has an aperture somewhat smaller than the sample to be punched.

3. The invention according to claim 1 comprising a collecting tray for the sample, which supports the punching plate.

4. The invention according to claim 1 wherein said mounting support comprises a U-shaped mounting support, which holds the actuating appliance on one end and the punching plate on the other end.

45 5. The invention according to claim 1 comprising two inflexible brackets to which the actuating appliance and the punching plate are mounted, to allow the material passing through between them.

6. The invention according to claim 1 comprising the said head fixed on said upper bush, by threads.

7. The invention according to claim 1 comprising a bell-shaped mounting support for said knife which causes a blast during movement, shifting the sample downwards.
